UNITED STATES PATENT OFFICE.

CHRISTIAN W. SVENDSEN, OF MATAWAN, NEW JERSEY.

HOLDER FOR TILES.

1,230,442.

Specification of Letters Patent.

Patented June 19, 1917.

Application filed December 15, 1915. Serial No. 66,951.

To all whom it may concern:

Be it known that I, CHRISTIAN W. SVENDSEN, a subject of the King of Denmark, and resident of Matawan, in the county of Mon-
5 mouth and State of New Jersey, have invented a new and useful Improvement in Holders for Tiles, of which the following is a specification.

This invention relates to an improvement 10 in tile holding devices with the object in view of providing a device which will hold a tile with its face in position to be dipped or glazed, at the same time protecting the back and side edges of the tile from coming 15 in contact with material with which the tile is to be coated, thereby preserving the surface used for cementing or securing the tile in place.

Another object is to provide a device 20 which will yieldingly hold a tile and which has a means for releasing the tile.

A further object is to provide certain improvements in the form, construction and arrangement of the several parts whereby 25 the above named and other objects may be effectively carried out.

A practical embodiment of my invention is represented in the accompanying drawings, in which,

30 Figure 1 represents a side elevation of the device having a tile held therein.

Fig. 2 is a front elevation of the same,

Fig. 3 represents a vertical section taken in the plane of the line A—A of Fig. 2, looking in the direction of the arrows,

Fig. 4 represents a transverse vertical section taken in a plane at right angles to Fig. 3,

Fig. 5 represents a front elevation of a 40 holder for another form of tile, and

Fig. 6 represents a vertical section taken in the plane of the line B—B of Fig. 5.

In the form shown in Figs. 1 to 4 inclusive, I have shown a device which is particularly well adapted to hold a cap molding tile.

The device comprises a fixed member denoted by 1, and a reciprocating member 2. The fixed member 1 is formed with a bottom 3, a front wall 4, a rear wall 5, and a vertical side wall 6, which walls are securely fastened to the bottom in any well known and approved manner, in position to embrace the edges of a tile 7. The fixed member 1 is also provided with a removable

handle 8 which is secured to a yoke 9 by means of a threaded pin 10 and nut 11. The yoke 9 is fastened to the bottom 3 by rivets 12.

The reciprocating member 2 is formed 60 with a vertical wall 13 which is adapted to be moved toward and away from the side wall 6, so as to engage the edge of the tile 7 diametrically opposite to the edge engaged by the wall 6. The vertical wall 13 is held 65 in a position so that it may reciprocate and be in contact with the bottom, front and rear walls by means of an overhanging bracket 14 secured to a bar 15 fitted to slide in guides 16 fixed to the bottom 3. The bar 70 15 is reciprocated by means of a manually operated lever 17 pivoted in a bracket 18 carried by the yoke 9 and having its free end 19 in position to engage a lug 20 fast on the bar 15. The bar is held at the limit 75 of its inward movement by a spring 21, one end of which is connected to the end of the bar 15 and the other end to a lug 22 fast on the bottom 3. The inner surfaces of the front and rear walls are provided with 80 strips of yielding material 23, such as rubber, which engage the edges of the tile 7, upon opposite sides and protect them from coming in contact with the liquid with which the face of the tile is to be coated. 85 The inner surface of the vertical side wall 6 is also provided with a pad of yielding material 24, such as rubber, which engages the edge of the tile adjacent thereto. The inner surface of the vertical wall 13 is like- 90 wise provided with a pad of yielding mate- 95 rial 25. These pads 24, 25 also serve to protect the edges of the tile from coming in contact with the liquid when the tile is being dipped or coated.

Thus it will be seen that when a tile is to be inserted, the lever 17 is swung toward the handle 8, as shown in dotted lines in Fig. 4, which swinging forces the bar 15, by means of the free end 19 of the lever 17 and 100 the lug 20 outwardly, thereby opening the space between the pads 24, 25, so that the tile may be pressed against the stops 26, 27, secured to the bottom 3 and the yielding strips 23 of the front and rear walls. Upon 105 releasing the lever 17, the spring 21 will force the wall 13 with its pad 25 against the tile, which in turn is pressed against the pad 24 of the wall 6, thereby protecting the edges of the tile as well as firmly hold- 110

2
ing it in the device so that it may be conveniently handled.

In Figs. 5 and 6, I have shown a device which is particularly well adapted to hold 5 what is known in the trade as a "Bull nose" tile.

While I have shown a device holding tiles of two different sizes and shapes, it will be understood that it is only necessary to substitute walls conforming to the periphery 10 of the tile to make the device applicable to any shape and size of tile to be treated.

Also, while I have shown and described my device as a tile holder, it is obvious that 15 it may be used for holding any article to be coated where a certain surface only is to be exposed.

It is evident that various changes might be resorted to in the form, construction and 20 arrangement of the several parts without departing from the spirit and scope of my invention, and hence I do not intend to be limited to the structure herein shown and described, but

25 What I claim is:

1. A holder for tiles to be coated comprising a bottom for protecting the back exterior surface of the tile and means constructed to coat with said bottom and yieldingly embrace the tile to protect the sides and ends of the tile while being coated.

2. A holder for tiles to be coated comprising a bottom for protecting the back exterior surface of the tile, means constructed 30 to coat with said bottom and yieldingly embrace the tile to protect the sides and ends of the tile while being coated, and means for releasing the tile.

3. A holder for tiles to be coated comprising a bottom for protecting the back exterior surface of the tile, means constructed to coat with said bottom and yieldingly embrace the tile to protect the sides and ends of the tile while being coated, said 40 means comprising a fixed member, a reciprocating member, and means for moving said reciprocating member.

4. A holder for tiles to be coated comprising a bottom for protecting the back exterior surface of the tile, means constructed to coat with said bottom and yieldingly embrace the tile to protect the sides and ends of the tile while being coated, said 50 means comprising a fixed member, a reciprocating member, means for moving said reciprocating member and a spring actuated

means interposed between said members for drawing them together.

5. A holder for tiles to be coated comprising a bottom for protecting the back exterior surface of the tile, means constructed to coat with said bottom and yieldingly embrace the tile to protect the sides and ends of the tile while being coated, said 60 means comprising a fixed member, a reciprocating member, said members having inwardly turned edges adapted to engage the tile, means for moving said reciprocating member, and a spring actuated means interposed between said members for drawing 65 them together.

6. A holder for tiles to be coated comprising a bottom for protecting the back exterior surface of the tile, means constructed to coat with said bottom and yieldingly embrace the tile to protect the sides and ends of the tile while being coated, said 70 means comprising a fixed member having a handle, a reciprocating member, means carried by the fixed member for moving said reciprocating member, and a spring actuated 75 means interposed between said members for drawing them together.

7. A holder for tiles to be coated, comprising means for removably holding the tile with only its surface to be coated, exposed, 80 said means comprising a fixed member having side, front and rear walls, a reciprocating member having a side wall, means for moving said reciprocating member in one direction and a spring-actuated 85 means interposed between said members for moving the reciprocating member in another direction.

8. A holder for tiles to be coated, comprising means for removably holding the tile with only its surface to be coated, exposed, 90 said means comprising a fixed member having side, front and rear walls, said walls being provided with yielding inner surfaces, a reciprocating member having a side wall, 95 said wall being provided with a yielding inner surface, means for moving the reciprocating member in one direction and a spring-actuated means interposed between 100 said members for moving the reciprocating member in another direction.

In testimony, that I claim the foregoing as my invention, I have signed my name this thirteenth day of December, 1915.

CHRISTIAN W. SVENDSEN.
